DESIGN FOR A HEEL

Charles O. Ryberg, Quincy, Mass.

Application July 8, 1937, Serial No. 70,297

Term of patent 7 years

To all whom it may concern:

Be it known that I, Charles O. Ryberg, a citizen of the United States, residing at Quincy, in the county of Norfolk and State of Massachusetts, have invented a new, original, and ornamental Design for Heels, of which the following is a specification, reference being had to the accompanying drawing, forming a part thereof.

I claim:

The ornamental design for a heel substantially as shown.

CHARLES O. RYBERG.
